UNITED STATES PATENT OFFICE.

JOHN WESLEY DU PUY, OF CLEVELAND, OHIO, ASSIGNOR TO THE CLEVELAND CO-OPERATIVE STOVE COMPANY, OF CLEVELAND, OHIO, A CORPORATION OF OHIO.

MOUNTING FOR A CLOSURE MEMBER.

Application filed September 3, 1925. Serial No. 54,252.

The present invention relates to a mounting for use with a closure member, such for instance, as a door for closing the opening of an oven of a stove, or for general use in 5 a similar or analogous construction.

The object of the invention is to provide a door or closure mounting in which the pivotal mounting or hinges for the door are concealed so that the appearance of the door 10 when in closed position shows no appearance of hinges on the outside thereof.

A further object is to provide a mounting in which the pivotal mounting is concealed, and the door is spring retained so that when 15 moved above its horizontal open position the door will be returned to its closed position by the spring action, and which mechanism will permit the door to be held in open position by the weight of the door.

Reference should be had to the accompanying drawing forming a part of this specification, in which Fig. 1 is a front elevation of a stove having a door embodying the present invention; Fig. 2 is a side elevation with portions in section showing a 20 part of the door mounting; Fig. 3 is a rear elevation showing a part of the door mounting; Fig. 4 is a side elevation with portions in section showing the door mounting; Fig. 25 5 is a fragmentary view in elevation showing a part of the door construction; Fig. 6 is an end elevation of the showing in Fig. 5; Fig. 7 is an elevation with portions in section showing the portion of the pivoting 30 mechanism which co-operates with that shown in Figs. 5 and 6.

In the drawings, the door is indicated by the reference numeral 1. This door at the 40 left and right lower corners is provided with a rounded extension 2 from which there laterally extends a finger 3, and there also extends a downwardly depending curved finger 4. The lower edge of the door is rounded as indicated at 5. In the drawings 45 6 indicates the front of the stove having a suitable opening for which the door 1 forms a closure, it being understood that the disclosure with respect to the stove is merely indicative of one form which the invention 50 may assume.

The portion of the front member 6 adjacent the lower edge of the door 1 is also rounded, as indicated at Fig. 7, and the inner end of the round portion 5 is closely po-

sitioned with respect to the lower edge of 55 the opening in the member 6 when the door 1 is in its closed position. At each side of the opening in the member 6 and upon the inside surface there is formed or otherwise secured a rounded projection 8. In the case 60 of a stove this projection 8 may be cast integral with parts of the stove front 6, or it may be separately formed and attached. The curvature of the member 8 and that of the downwardly extending finger 4 which is 65 carried by the door is the same so that when the door is mounted within the opening in the stove front 6 the rounded finger 4 will lie against the curved surface of the member 8, and when the door is moved to its open 70 and closed position the rounded finger 4 will slide upon the rounded surface of the member 8.

It will be understood that the projecting member 8 is duplicated upon opposite sides 75 of the opening in the stove front, and likewise the projecting fingers 3 and 4 are duplicated at opposite left and right lower corners of the door.

To the finger 3 there is attached one end 80 of a spring 9, the opposite end of the spring being secured to a portion of the rear surface of the stove front, as clearly indicated at 10 in Fig. 4.

The point of attachment of the spring 9 85 upon the arm 3 is such that when the door is in closed position, as indicated in full lines in Fig. 4, the pull of the spring is off center with respect to the pivotal mounting 90 of the door, and therefore the door is held in its closed position. When the door is moved to open position, as indicated in dotted lines in Fig. 4, the pivotal point of the spring 9 upon the arm 3 is moved so that it is substantially in line with the center of 95 the pivot of the door, and this condition added to the fact that the weight of the door in its open position is overhanging, is sufficient to overcome the retractive effort 100 of the spring 9 so that the door will remain in open position. However, when the door is raised through a part of its movement to closed position, the action of the springs will become effective and return the door to its closed position.

As before described, the lower edge of the door 1 is rounded, as indicated in Fig. 2, and this construction in conjunction with the

movement of the curved arms 4 about the projections 8 before described, causes the edge of the door to move away from the rounded lower edge of the opening in the stove front 6 as the cover is moved to its open position.

The action of the co-operating members which form the pivot for the door may be described as a cantilever action.

10 In order to insure that the curved arms 4 carried by the door, and the members 8, shall stay in contact at all times, it is desirable to provide guards, one of which guards is indicated at 11 in Figs. 2 and 3. These guards 15 are formed with an inner curved surface 12 which is a complement of the curved surface on the member 8. Therefore, the curved finger 4 may move upon the curved surface of the member 8 without hindrance, due to 20 the presence of the guard. At the same time this guard will prevent the accidental displacement of the curved fingers 4 with respect to the members 8 with which they co-operate. The guard 11 is secured at its ends 25 upon the inside of the stove front.

From the construction as it is described, it will be seen that the entire pivotal mounting for the door is behind the stove front, and no part of it is visible from the outside 30 of the stove front, nor are there any outwardly extending hinges or parts of hinges or pivotal mountings such as are customarily employed in connection with stove doors and structures of similar nature.

35 Having described my invention, I claim:—
1. The combination with a member having an opening therein, of a closure for said opening, said closure having rearwardly extending portions at opposite sides thereof 40 with a depending curved arm, extensions carried by the said member adjacent the opening and upon the inside of the said member, having a curved surface with which the inner surface of said curved arms on the closure co-operate, and resilient means co-operating with the said closure and tending to return the closure to closed position when the closure is intermediate between open and closed positions.

50 2. The combination with a member having an opening therein, of a closure for said opening, said closure having rearwardly extending portions at opposite sides thereof, with a depending curved arm having a surface which is a part of the circumference of a circle, extensions carried by the said member adjacent the said opening and upon the inside of said member, which extensions have a curved surface forming a part of a circumference of a circle of the same radius as the curvature of the said arms, the said arms being adapted to slide upon the surface of the said extensions when the closure is moved to open and closed position, and resilient means co-operating with said closure 55

and tending to return the closure to closed position when the closure is intermediate between open and closed positions.

3. The combination with a member having an opening therein, of a closure for said opening, said closure having rearwardly extending portions at opposite sides thereof with a depending curved arm, extensions carried by the said member adjacent the opening and upon the inside of the said member having a curved surface with which the inner surface of said curved arms on the closure co-operate, spring members having one end thereof secured to the said member and the other end secured to the closure adjacent the said curved arms, said springs being extended as the closure is moved to open position and tending to return the closure to closed position when the same is intermediate between open and closed positions. 85

4. The combination with a member having an opening therein, of a closure for said opening, said closure having rearwardly extending portions at opposite sides thereof, with a depending curved arm having a surface which is a part of the circumference of a circle, extensions carried by the said member adjacent the said opening and upon the inside of said member, which extensions have a curved surface forming a part of a circumference of a circle of the same radius as the curvature of the said arms, the said arms being adapted to slide upon the surface of the said extensions when the closure is moved to open and closed position, 90 spring members having one end thereof secured to the said member and the other end of each spring member secured to the closure adjacent an end of the rearwardly extending portion, said spring members being extended when the closure is moved to open position, and the attaching point of the spring to the said closure member moving to a point beyond the center of curvature of the said curved extensions on the said member whereby the closure will remain open when moved to open position, said springs tending to return the closure to closed position when the same is intermediate between open and closed positions. 100

5. The combination of a member having an opening therein, of a closure for said opening, said closure having rearwardly extending portions at opposite sides thereof with a depending curved arm, and a second arm extending at substantially right angles to said curved arm, extensions carried by the said member adjacent the opening, each of said extensions having a curved surface which is complementary to the surface of the depending curved arms and with which surface the said curved arms on the closure co-operate, and spring members having one end thereof attached to the said second arms carried by the closure and the other 110 120 125 130

end secured to the first mentioned member, whereby the axis of the spring is carried beyond the center of curvature of the said curved extensions carried by the first mentioned member when the closure is in open position, thereby to permit the closure member to remain in open position and said springs tending to return the closure to closed position when the closure is intermediate between open and closed positions.

6. The combination with a member having an opening therein the lower edge of said member adjacent said opening being curved inwardly, of a closure member for said opening, said closure having rearwardly extending portions at opposite sides thereof with depending curved arms, extensions carried by the said member adjacent the opening, which extensions have a curved surface with which the inner surface of the curved arms co-operate, and resilient means co-operating with the said closure and tending to return the closure to closed posi-

tion when the same is intermediate between open and closed positions.

7. The combination with a member having an opening therein, of a closure for said opening, said closure having rearwardly extending portions at opposite sides thereof with depending curved arms, extensions carried by the said member adjacent the openings and having a curved surface with which the said curved arms co-operate, guards secured at both ends to the first mentioned member and each having an inner curved surface corresponding with the curve on the said extensions and spaced from said extensions to form an enclosed slot, each curved arm moving inside the enclosed slot, and resilient means co-operating with said closure and tending to return the closure to closed position when the closure is intermediate between open and closed positions.

In testimony whereof, I hereunto affix my signature.

JOHN WESLEY DU PUY.
